Primary Examiner — Cynthia Ramirez(74) *Attorney, Agent, or Firm* — Ryan Kromholz & Manion, S.C.**(57) CLAIM**

The ornamental design for a recycling structure, as shown and described.

DESCRIPTION

FIG. 1 is a perspective view of a recycling structure showing our new design;

FIG. 2 is a top plan view thereof;

FIG. 3 is a bottom plan view thereof;

FIG. 4 is a front elevation view, the rear elevation being identical; and,

FIG. 5 is a right side elevation view, the left side elevation view being identical.

1 Claim, 2 Drawing Sheets(56)
